CLAIM

The ornamental design for a handle for a laparoscopic surgery instrument, as shown and described.

DESCRIPTION

FIG. 1 is a rear right perspective view of a handle for laparoscopic surgery instrument;

FIG. 2 is a rear right detailed perspective view thereof;

FIG. 3 is a right side view thereof;

FIG. 4 is a left side view thereof;

FIG. 5 is a front end view thereof;

FIG. 6 is a back end view thereof;

FIG. 7 is a top view thereof; and,

FIG. 8 is a bottom view thereof.

All features illustrated in broken line are expressly disclaimed and form no part of the claimed design.

1 Claim, 6 Drawing Sheets
